ATTY

UNITED STATES PATENT OFFICE.

WILLIAM K. ELSON, OF MARTIN'S FERRY, OHIO.

CASTER.

SPECIFICATION forming part of Letters Patent No. 293,156, dated February 5, 1884.

Application filed December 1, 1883. (No model.)

To all whom it may concern:

Be it known that I, WILLIAM K. ELSON, of Martin's Ferry, in the county of Belmont and State of Ohio, have invented a new and useful Improvement in Glass or Earthenware Casters; and I do hereby declare that the following is a full and exact description of the same, reference being had to the accompanying drawing, and to the letters of reference marked thereon.

10 The present invention has in view the production of a glass or earthenware caster or cruet-stand which shall be cheap to manufacture and at the same time be convenient and durable, and attractive in appearance.

15 The invention therein consists in the construction of the cruet support or base, which is preferably of annular form, mounted centrally upon a supporting-foot, and this support or base is pressed complete in one mold, with a central and four outer cruet-receptacles, the latter contiguous to the former, and all dependent from the under side of said base, and with means for receiving the ends of a spring-metal bail, and means for holding the same in 25 a vertical position, all as more fully hereinafter described and claimed.

For the better understanding of my invention, and to enable those skilled in the art to know how to properly construct the same, reference should be had to the accompanying drawing, in which is illustrated a perspective view of a caster constructed in accordance with this invention, and representing a cruet in one of the outer sockets.

30 A denotes the supporting-foot, made of glass or earthenware, and preferably of a shape or fashion after that of other well-known glass articles and metal casters. This foot is pressed in a mold, and is welded while hot to the support or base. Upon the upright stem of this foot is centrally supported the cruet support or base B, which is preferably of annular form, and is pressed complete in one mold, with a center socket or receptacle, C, and four outer 40 sockets or receptacles, C', all for the accommodation of cruets. As illustrated, these cruet-receptacles are square, and depend from the under side of the base B, and those alluded to as the "outer" sockets have one side contiguous 45 to one side of the center socket, C, or, in other

words, they are located around the periphery of the support or base B at points where two lines would terminate if drawn at right angles across the center of said support or base. In thus locating the cruet sockets or receptacles 55 the inlet to the mold is just large enough to receive a sufficient amount of the molten material to form the base and its sockets, with an intervening space, a, between the outer facing sides of the outer sockets, C', thus effecting a 60 great saving of material.

D represents a spring-metal bail, the ends of which are sprung into sockets or ears b b, pressed in the same mold with the support or base B, and located upon the peripheral sides 65 of two of the outer sockets, C', at points diametrically opposite. This bail is adapted to be held in a vertical rigid position by means of notches e e, formed upon the periphery of the support or base B at points above the sockets 70 or ears b b.

From the foregoing description it will be manifest that, in lieu of the support or base B being made annular and the cruet-receptacles square, these forms may be reversed; but for 75 convenience and economy in manufacture and durability in use the herein-described forms are preferred.

Having thus described my invention, what I claim, and desire to secure by Letters Patent, 80 is—

1. A glass or earthenware caster provided with a detachable bail applied to maintain a vertical rigid position, substantially as set forth.

2. A glass or earthenware caster having its cruet support or base pressed complete in one mold, with a central cruet-receptacle and four outer receptacles contiguous thereto, all dependent from the under side of said support 90 or base, substantially as described.

3. A glass or earthenware caster having its cruet support or base pressed complete in one mold, with a central cruet-receptacle and four outer receptacles contiguous thereto, and centrally mounted upon a supporting-foot welded to the support with glass, substantially as described.

4. The combination, in a glass or earthenware caster having a detachable bail, of the 100

cruet support or base centrally mounted upon a supporting-foot, both parts being pressed separately in molds and welded together when hot, the support provided with a central cruet-receptacle, four outer receptacles contiguous thereto, means for receiving the ends of the bail, and means for holding the bail in a ver-

tical rigid position, substantially as described.

In testimony whereof I affix my signature in presence of two witnesses.

WILLIAM K. ELSON.
